UNITED STATES PATENT OFFICE.

JAMES F. HINES, OF CLEVELAND, OHIO, ASSIGNOR, BY DIRECT AND MESNE ASSIGNMENTS, OF ONE-THIRD TO JOHN M. SARVER AND ONE-THIRD TO JOSEPH K. BYE, BOTH OF COLUMBUS, OHIO.

CURTAIN-POLE.

1,278,348.

Specification of Letters Patent. Patented Sept. 10, 1918.

Application filed October 4, 1915. Serial No. 53,919.

To all whom it may concern:

Be it known that I, JAMES F. HINES, a citizen of the United States, residing at Cleveland, in the county of Cuyahoga and 5 State of Ohio, have invented certain new and useful Improvements in Curtain-Poles, of which the following is a specification.

The invention relates to parallel poles for hanging curtains or draperies at the top of a 10 window or elsewhere, and the object of the improvement is to provide a pivotal support at one end of the poles for permitting the curtains to be uniformly draped without obstruction from end to end of the 15 poles, and also for permitting the poles with the curtains thereon to be swung on their pivoted end away from the window without binding or bunching the curtains or impinging the window frame at the pivoted 20 end of the poles.

These objects and other advantages are attained by the construction and arrangement illustrated in the accompanying drawing, in which—

25 Figure 1 is a plan view of two curtain poles showing the pivotal support therefor;

Fig. 2, a perspective view of the same parts showing the poles and bracket parts separated from each other;

30 Fig. 3, a plan view of the pivotal support showing the relation of the parts when the poles are rotated into various positions; and

Fig. 4, an outer end view of the pole bracket.

35 Similar numerals refer to similar parts throughout the drawings.

The pivotal support 1 for the curtain pole, includes the supporting bracket 2 secured to one side of the window frame, and 40 the pole bracket 3 secured on one end of the curtain pole.

The supporting bracket is preferably formed with the base plate 4 having ears 5 on each side with slots or apertures 6 45 therein, for securing the bracket to the side of the window by means of the screws 7.

The supporting bracket is also formed with the forwardly extending shank 8 which is made of sufficient vertical depth 50 to rigidly sustain the supporting head 9 which is formed on the forward end of the stem.

The vertical journal bearing or socket 10 is formed in the head of the supporting 55 bracket and is made of such a substantial

length as will securely support the pivot stem 11 of the pole bracket.

The pole bracket 3 is formed with the pendent pivot stem 11 which is made to neatly fit and rotate in the journal bearing 60 10 in the supporting head, and at the upper end of the pivot stem is formed the annular shoulder 12 adapted to bear and rotate upon the upper end 13 of the supporting 65 head.

The body 14 of the pole bracket extends across the upper end of the pendent pivot stem, and on each end of the body portion are provided two relatively short arms 15 extending in one direction from the pivot 70 stem, and the two relatively long arms 16 extending in the opposite directions from the pivot stem; which arms are arranged parallel with each other and the corresponding arms are adapted to engage and 75 support the ends of the curtain or drapery poles 17 and 17^a.

Each short arm of the pole bracket is provided with a cylindric socket 18 adapted to receive and engage the end portion of the 80 corresponding pole. This arm is preferably made in semi-spherical form, thus inclosing the end of the curtain pole and forming a round smooth end for the curtain bracket.

Each long arm 16 of the pole bracket is 85 cylindrically concaved on its upper side in extension of and coaxial with the cylindric socket formed in the short arm thereof, thus forming a supporting seat for a considerable portion of the curtain pole extending a substantial distance along the under side thereof from the pivoted body portion of the pole bracket.

The tops and sides of the long arms of the pole bracket are cut away so as to freely 95 expose the tops and sides of the curtain poles, excepting only the extreme ends thereof of which are entered and secured in the cylindric sockets in the short arms of the bracket. By this formation of the bracket it 100 is evident that curtains may be uniformly draped upon the poles throughout their entire length without being obstructed or interfered with by the pole bracket. Suitable apertures 20 are preferably provided in the 105 ends of the long arms of the bracket, through which apertures screws 21 may be passed for securing the poles in the seats and sockets formed by the pole bracket.

The parts are so proportioned and ar- 110

ranged that the extreme length of the short arms of the pole bracket are only about half the length of the shank of the supporting bracket, as shown in Fig. 3, so that the free 5 end of the pole can be rotated directly outward without any portion of its pivotal bracket impinging the frame of the window; and it is also evident that curtains may be draped over and beyond the extreme ends 10 of the poles and their pivotal bracket, and made fast to the window frame, without being bunched or crushed against the window frame when the free ends of the poles are swung away therefrom.

15 The long arms of the pole brackets are extended a substantial distance along the under sides of the poles, to give sufficient leverage with reference to the ends of the poles which are secured in the short arms 20 of the bracket, so as to firmly sustain the free ends of the poles from sagging, excepting as the pole may bend from its own elasticity. Such an extension of the long arms of the pole bracket is made to compensate 25 for the necessity of making the other arms short enough to permit the bracket and the curtains draped thereover to swing inward without impinging or bunching against the window frame.

Copies of this patent may be obtained for five cents each, by addressing the "Commissioner of Patents, Washington, D. C."

I claim:—

1. A pivotal support for the end of a curtain pole including a supporting bracket having a shank with a head thereon, and a pole bracket having a pendent stem pivoted on the supporting head, a cross 35 body on the upper end of the pendent stem, two relatively short arms extending in one direction from the ends of the cross body for engaging the ends of the curtain poles, and two relatively long arms extending in 40 the opposite direction from the cross body forming seats for the curtain poles reaching a substantial distance along their under sides from the pivoted body portion of the bracket. 45

2. A bracket for curtain poles comprising a pendent pivot stem, a cross body thereon, and two relatively short arms extending in one direction from the ends of the cross body for engaging the ends of the curtain 50 poles, and two relatively long arms extending in the opposite direction from the cross body forming seats for the curtain poles reaching a substantial distance along their under sides from the pivoted body portion 55 of the bracket.

JAMES F. HINES.
